UNITED STATES PATENT OFFICE

EDWARD O. HERMANN, OF MILL VALLEY, CALIFORNIA, ASSIGNOR TO COBB CONNECTOR COMPANY, OF LOS ANGELES, CALIFORNIA, A CORPORATION OF ARIZONA

TRAIN-PIPE COUPLER

Application filed September 12, 1928. Serial No. 305,461.

My present invention relates to means for connecting the air and steam pipes of adjacent railway cars and particularly to a coupler head wherein pneumatic pressure is operative to maintain the heads in sealed engagement.

In a prior patent to John L. Cobb, Number 1,173,997, dated February 29, 1916, and assigned to the assignee of this application, 10 there is disclosed a coupler of the type contemplated by my invention and it is an object of my present invention to provide a coupler head having certain features of improvement over the coupler head disclosed in this 15 patent.

Another object of my invention is to provide means whereby the pneumatic pressure within the train pipe line may be utilized to securely hold the cooperating couplers together and seal the joint when the same are 20 in operation.

A further object of my invention is to provide a coupler head having means in cooperation with the pressure responsive features 25 which will become operative to prevent damage thereto, should the coupler head become uncoupled while the train brake pipe line is energized.

Another object of my invention is to provide means whereby my coupler head may be 30 readily opened up so as to facilitate inspection and repair of the normal wearing parts.

Other objects and advantages will appear 35 as the description, taken in connection with the accompanying drawings, proceeds.

For a better understanding of my invention, reference should be had to the accompanying drawings, wherein I have shown by way of illustration a preferred embodiment 40 of my invention. It is to be understood that in adapting the same to meet the many conditions that may arise, various changes in the shape, form, proportions, and minor details of construction may be resorted to without departing from the spirit of my invention.

In the drawings—

Figure 1 is a plan view of two cooperating 50 coupler heads taken in section along the horizontal center line thereof,

Figure 2 is a side elevation of one of the coupler heads shown in Figure 1,

Figure 3 is a side elevation of the other coupler head shown in Figure 1 with the hinged guide member removed therefrom,

Figure 4 is a front end view of the coupler head shown in Figure 2,

Figure 5 is a view similar to Figure 4 taken in section along the center line of the ports at V—V, and

Figure 6 is a sectional view taken along line VI—VI of Figure 2.

In brief, my improved coupler contemplates a pair of duplicate coupler heads, each provided with a tongue member having ports in the engaging faces thereof; a hinged guide member having flared ends for guiding the cooperating tongues into engagement; a wear plate operating to take the normal wear while in use and hold the ports out of engagement until they are aligned; and an improved means responsive to pneumatic pressure adapted to cooperate with the hinged member and force the coupler ports into sealed engagement when the heads are fully coupled.

For an understanding of the details of construction of my invention, reference should be had to the figures of the drawings wherein like numerals designate like parts.

In Figure 1, 10 designates the tongue portion of my improved coupler and 11 designates the hinged guide member. This guide member 11 is hinged to the rear portion of the coupler head at the point 12 and carries a suitable latching element 13 which is adapted to engage recesses formed upon the coupler head and function to retain the guide member 11 rigid with respect to the head when latched. From this figure of the drawings, it will be seen that the guide member 11 forms in conjunction with the coupler tongue 10 a receptacle or throat into which the other tongue 10 will project when the couplers are in operation. The tongues 10 are divided up vertically into a plurality of independent chambers and ports are arranged in the engaging faces of the tongues 10 in communication with these chambers so that when the coupler heads are engaged a communication between the corresponding chambers of the 100

co-operating coupler heads will be effected. At the rear of the coupler head and also communicating with the above referred to chambers, there are provided suitable inlets to which the train pipe lines may be connected 5 for the purpose of establishing a connection between the adjacent cars, as is well understood. The ports in the engaging faces of the tongues 10 are each provided with suitable compressible gaskets and immediately in 10 advance of these gaskets there is formed a raised or wearing surface 14 upon the face of the tongue. These raised or wearing surfaces project inwardly from the ends of the tongues 10 and terminate at a point approximately 15 in line with the centers of the above referred to ports so that as the coupler tongues are brought into engagement, the ports with their compressible gaskets will be held out of contact with the adjacent coupler heads 20 and thus protected against displacement.

In the back wall of the chamber immediately behind the central or train brake pipe chamber of the coupler head, there is formed 25 a compartment 15 which communicates by means of a small port 16 with the interior of the aforesaid chamber and arranged in the chamber 15 there is provided a flexible diaphragm 17 which is preferably of an impregnated fabric or other non-metallic material. 30 This diaphragm 17 is adapted to flex within the compartment 15 under the influence of fluid pressure exerted thereupon through the opening 16 when the coupler heads are in operation and also cooperates with a suitable 35 plunger or piston 18 to force the aligned ports with their compressible gaskets into sealed engagement when the coupler heads are properly connected and energized. The piston 18 is circular in cross section and its inner end 40 slides freely through a member 19 which forms the securing means for the diaphragm 17 of the compartment 15. The outer end of the piston 18 is adapted to slide freely 45 through a removable plate 20 which is secured to the back face of the coupler. This plate 50 is of rectangular shape and is countersunk so that a smooth surface will be presented at the back of the coupler and it carries on its inner surface a leaf spring member 21 which projects diametrically through an opening 22 55 formed in the piston 18. The leaf spring 21 is secured to the member 20 at one end and contacts at its other end in sliding engagement so that it may yield and permit the piston 18 to move outwardly and engage the adjacent surface 23 of the guide member 11 and thus in cooperation therewith force the 60 coupler heads together when the diaphragm 17 is flexed due to the existence of pneumatic pressure within the coupler head train brake pipe chamber.

In order that the aligned ports will be brought into sufficiently close contact to permit the establishment of an initial pressure

behind the diaphragms 17, I provide in the end of the throat formed by the tongue 10 and guide 11 a spring 24 which is mounted upon the latter and is of such shape that it will engage the extreme end of the tongue and urge it with its ports toward the ports of the 70 adjacent or cooperating coupler head.

In Figure 2, the position of the plunger 18 upon the back face of the coupler head is very clearly shown, as is also the shape and arrangement of the retaining plate 20. This figure also shows the position of the leaf spring 21 and the plunger guide 19 as having semi-circular openings 25 which prevent a building up of pressure on this side of the diaphragm which might act to prevent a flexing of the diaphragm, as previously suggested. The external vertical outlet of the coupler is also very well shown in this view and particularly the location of supporting bosses 26 by means of which the coupler head is attached to its supporting gear and also the degree of flaring at the ends 27 of the guide member 11. In this view of the drawings, there is also shown a connection inlet 28 which enters the upper or signal air chamber of the coupler head and a second connection inlet 29 which communicates with the train brake pipe chamber of the coupler head. Below these connection inlets 28 and 29 there is provided a downward projection on the coupler head which terminates in a third connection inlet 30 to which the train steam line may be connected.

By referring to Figure 3, it will be seen 100 that this arrangement of the connection inlet 30 below the body of the coupler head is necessitated by reason of the hinge providing bosses 31 to which the hinge arm 11 is attached. This view of the drawings also 105 shows a pair of overhanging arms 32 and 33 which cooperate with the latch 13 to maintain the hinge guide 11 in its operative position. These members 32 and 33 are provided respectively with undercut notches 34 and 35 110 into which the ends of the latch 13 project when the latter is in its operative position. The connecting ports of the coupler head are shown here as arranged vertically in alignment and are designated by the numerals 36, 37, and 38, 36 being the smallest and arranged 115 within the train pipe signal air line; the port 37 being arranged in the train brake pipe line; and the port 38 being arranged in the train steam pipe line. This view of the drawing also very clearly shows the shape and disposition of the previously referred to raised or wearing surface 14 upon the face of the tongue 10. This surface is here shown as being cut away around the ports 36, 37, 120 and 38 and projecting therebetween to a point where it terminates gradually, substantially in alignment with the vertical center line of the ports. By tapering the wearing surfaces 125 14 of each of the coupler faces in this manner, 130

it will be seen that after they have passed over each other, the two tapered surfaces will slide down upon each other and permit the gaskets arranged in the ports to come into contact with each other. The gaskets are illustrated in Figures 1 and 5 and at this point it might be said that they are of such dimensions that they will project slightly above the surface of the ports so that when the wearing surfaces 14 of the cooperating coupler heads slide over each other, the gaskets will be brought under compression and thus effect a tight seal therebetween.

In Figure 4, the supporting bosses 26 are shown as mounted upon spaced parallel webs 39 and the flared ends 27 of the hinged arm 11 are shown as projecting inwardly toward the tongue 10 so as to engage the approaching tongue 10 and guide it into its proper position adjacent the cooperating tongue.

In Figure 5, the latch 13 is shown in its guide securing position and interlocking with the projecting arms 32 and 33, as previously described. This latch 13 is mounted centrally and pivotally upon the hinge member 11 by means of a suitable stud 40 and is provided with an operating lever 41 which operates in conjunction with a set screw 42 carried thereby to maintain the latch 13 in its guide latching position, the set screw 42 being positively engaged in the end of the arm 32. This figure also shows in section the ports 36, 37, and 38 and their arrangement with respect to the signal air, train pipe air, and steam chambers of the coupler head. The port 16 which connects the train pipe air line with the chamber 15 is also very clearly shown in this view, as is also the manner of mounting and retaining the plunger 18 in position.

In connection with the showing of Figure 6, it is thought that no further explanation is necessary.

From the above, it will be seen that I have provided a new and novel train pipe coupler having many improved features which are not disclosed in the prior art.

Having thus described my invention, what I claim and desire to secure by Letters Patent is—

1. In a train pipe coupler, the combination of a pair of cooperating couplers comprising interlocking heads having ports in their engaging faces adapted to align when the couplers are in operation, a chamber formed in each of said heads opposite said ports and communicating with the interior thereof, a non-metallic diaphragm arranged in said chamber and exposed on one side to fluid pressure when said heads are coupled, and a plunger movably mounted adjacent said diaphragm and actuated thereby, said plunger engaging a part of the cooperating coupler head to press said heads with their aligned ports into sealed engagement.

2. In a train pipe coupler, the combination

of a pair of cooperating couplers comprising interlocking heads having ports in their engaging faces adapted to align when the couplers are in operation, a chamber formed in each of said heads opposite said ports and communicating with the interior thereof, a diaphragm arranged in said chamber and exposed on one side to fluid pressure when said heads are coupled, a member movably mounted adjacent said diaphragm adapted to engage a part of the cooperating coupler head and press said heads with their aligned ports into sealed engagement, and a spring cooperating with said member for holding it in engagement with said diaphragm.

3. A port sealing mechanism for train pipe couplers comprising a chamber formed in the back of each of the coupler heads communicating with the interior thereof, a non-metallic diaphragm arranged within said chamber exposed on one side to the fluid pressure within the head, and a movable member projecting into said chamber adapted to be forced outwardly when pressure is exerted upon said diaphragm and cooperate with an interlocking part of said cooperating head to hold the ports in sealed engagement.

4. A port sealing mechanism for train pipe couplers comprising a chamber formed in the back of each of the coupler heads communicating with the interior thereof, a diaphragm arranged within said chamber exposed on one side to the fluid pressure within the head, a movable member projecting into said chamber adapted to be forced outwardly when pressure is exerted upon said diaphragm and cooperate with an interlocking part of said cooperating head to hold the ports in sealed engagement, said member having an opening extending therethrough intermediate its ends, and a leaf spring extending through said opening adapted to hold said member in operative engagement with said diaphragm.

5. In a train pipe coupler, the combination of a pair of cooperating coupler heads having ports in the sides thereof adapted to slide into engagement with each other, a hinged member adapted to guide said coupler ports into engagement when operative and to be released to permit repair and inspection of said ports, a plunger adapted to be moved by fluid pressure into engagement with said hinged member and force said ports into sealed engagement when said couplers are energized, and means projecting through said plunger adapted to retain it in an operative position and prevent excessive displacement thereof should said hinged member be released while said coupler heads are energized.
